FREDERICK C. BAUER, JR., OF CAMDEN, NEW JERSEY

EXCAVATION MULTIPLE-SECTION CASING OR CISTERN

Application filed July 25, 1927. Serial No. 208,394.

This invention relates to the art of plumbing and appliances for facilitating plumbing work, and more especially to an excavating multiple section casing or cistern, and an important purpose of the invention is to provide, in a device of this kind, a construction for saving life and at the same time to expedite excavating.

In the plumbing industry it is very often necessary to excavate holes for the installation of plumbing, such as water mains, sewers and various piping from the mains into various buildings. It frequently occurs that such excavations cave in at their sides and bury the laborer and therefore endanger life, as it is very difficult at times to extricate the laborer in time. At present it is customary to board up the wall of the excavation, and even under these conditions, there are times when the wall of the excavation caves in.

Therefore it is the purpose of the present invention to provide an improved multiple section excavating casing or cistern, which may be lowered into the excavation step by step, that is section by section, and when the casing or cistern has been lowered according to the depth of the excavation desired, the wall of the excavation or hole is prevented from caving in on the laborer, therefore avoiding endangering life.

In a device of this character it is another purpose to provide a multiple section or cistern, wherein the sections are nested on the surface of the ground at the location where the excavation is to be made, that is the sections are telescopically nested. As the excavation deepens the smaller section lowers correspondingly, and likewise the succeeding sections, and when the sections are properly positioned in the excavation there are means so interconnecting the sections and supporting the sections consecutively from the bottom to the top as to retain the casing or cistern in position.

A further purpose is to provide each of the cisterns from the top section to the bottom section with exterior round rings or hoops, which are welded to the sections thereby providing annular shoulders to rest upon

and engage with similar interior annular shoulders at the lower edge of the sections, so that the sections may be consecutively supported from the top to the bottom of the excavation.

A still further purpose is to provide suitable handles formed on the exterior shoulders or hoops, so that hooks depending from a clevis link (which may be suspended from a tripod supported pulley and chain or rope) so that the several sections may be extricated or removed after the piping or plumbing has been installed.

A still further purpose is to provide the several sections of the casing or cistern with the plurality of foot or hand holds, by which a laborer may climb out of the casing when the excavation is complete, or as the sections are removed. In other words the laborer may climb out a certain distance from the bottom section to the adjacent section and connect the hooks to the bottom section and when it is removed he may climb to the next section and so on until the several sections are entirely removed and the laborer likewise out of the excavation.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Figure 1—is a view in section showing the top section in a position, when the excavation is started, said section being partly lowered.

Figure 2—is a similar view, with two more sections as having been lowered into the excavations as the latter deepens.

Figure 3—is a view showing all the sections lowered, and illustrating a tripod with suspending hooks engaged with the handles of the lowered section for the purpose of extricating the sections.

Figure 4—is an enlarged detailed section

view of a portion of one of the sections showing the construction and arrangement of the hook or shoulder, and its handles as having been welded to the sections.

5 Figure 5—is a view of a modified construction of handle.

Figure 6—is a top plan view of one of the sections.

Referring to the drawings, 1 identifies an 10 excavation, and 2 the multiple section casing or cistern, which comprises a plurality of sections 3, 4, 5, 6 and 7, it being understood that any number of sections may be employed and they may be any height or diameter. 15 However, the sections from the top to the bottom of the casing are of gradual decreasing diameter, so that the various sections may be nested and telescopically connected one within the other from the top to the bottom of the casing.

20 The several sections are provided with hand or foot holds 8, by which a laborer may climb out of the cistern or casing at any time and particularly when the excavation is completed.

25 In order to support the various sections in consecutive order from the top to the bottom of the casing, the sections are provided with exterior shoulders or hoops 9, which are in 30 the form of round rings welded or otherwise secured to the exterior of the sections as at 10. These exterior shoulders engage with similar shoulders 16, which are in the form of round hoop rings welded to the inner surface of the sections at their lower ends. These 35 hoops constituting shoulders are formed with integral handles 11, that is, the hoops are bent as shown causing the handles to be formed. The handles are deflected inwardly 40 of the casing, so as to permit hooks 12 carried by a clevis ring 13 suspended from a tripod 14, to engage with the hooks between the hooks and the inner surface of the sections, as shown clearly in Figure 3, and as 45 illustrated in the detailed view of Figure 4. In other words the hooks may engage with the handles from the outside in permitting the wall of the casing to retain the handles in position and in engagement with the 50 handles.

55 However, as shown in Figure 5 the hooks may engage with the handles from the inside out. However the sections may be removed from the excavation in the following manner. For instance when it is desired to remove the sections the hooks may engage with the handles of the lowermost section and such section elevated to the surface of the ground by 60 the pulleys and rope and chain connections. Then the hooks may again be lowered and engaged with the handles of the next section and so on until the several sections have been elevated to the surface of the ground and 65 removed.

The invention having been set forth what is claimed is:

As an article of manufacture, an excavating casing, comprising a plurality of sections extensible into an excavation as it deepens by a telescopic union between the sections, a round hoop ring welded on the interior of and adjacent the lower extreme end of each section, round hoop rings welded on the exterior adjacent the extreme upper end of each section, the latter rings to abut the former rings when each section is lowered telescopically within a preceding section, the last mentioned rings having diametrically opposite loop handles, said handles being directed upwardly and deflected inwardly and formed from the rings themselves, the construction and arrangement of the handles being such as to provide for sufficient space between the handles and the preceding section as to enable extricating hooks to engage with the handles between the inner surface of the casing and the handles, whereby each section can be lowered into the excavation or extracted therefrom.
